Primary Examiner—Martie Thompson**Attorney, Agent, or Firm**—Lockwood, Alex, Fitzgibbon & Cummings**[57] CLAIM**

The ornamental design for a clip and card holder, as shown and described.

DESCRIPTION

FIG. 1 is a perspective view of a clip and card holder showing our new design, the card and paper clip depicted by means of broken lines being shown for illustrative purposes only and forming no part of the claimed design;

FIG. 2 is a front elevational view thereof;

FIG. 3 is a top plan view thereof;

FIG. 4 is a rear elevational view thereof;

FIG. 5 is an elevational view of the left side thereof;

FIG. 6 is an elevational view of the right side thereof; and,
FIG. 7 is a bottom plan view thereof.
